OPHTHALMIC LENS CHIPPING CABINET

Joseph A. Wycoski, Silver Spring, Md., and Thomas T. Matsuura, Setagaya-ku, Tokyo, Japan

Application March 2, 1956, Serial No. 40,442

Term of patent 14 years

(Cl. D57—1)

Fig. 1.

Fig. 2.

Fig. 3.

Fig. 1 is a perspective view of an ophthalmic lens chipping cabinet, embodying the new design;

Fig. 2 is an end elevation; and

Fig. 3 is a top plan view of the cabinet.

The sides of the cabinet which are not shown are like those sides which are shown.

We claim:

The ornamental design for an ophthalmic lens chipping cabinet as shown and described.
